[57] CLAIM

The ornamental design for a portable computer terminal
housing for accessing and inputting patient medical
data, as shown and described.

DESCRIPTION

FIG. 1 is a top perspective view of a portable computer terminal housing for accessing and inputting patient medical data showing my new design;

FIG. 2 is a side elevational view thereof, the opposite side being a mirror image;

FIG. 3 is a bottom plan view thereof on a reduced scale.

FIG. 1

FIG. 2

FIG. 3
